UNITED STATES PATENT OFFICE.

CHARLES D. SHEPARD, OF NEW YORK, N. Y.

CENTRIFUGAL LIQUID-SEPARATOR.

SPECIFICATION forming part of Letters Patent No. 379,133, dated March 6, 1888.

Application filed May 9, 1887. Serial No. 237,612. (No model.)

To all whom it may concern:

Be it known that I, CHARLES D. SHEPARD, a citizen of the United States, residing at New York, in the county of New York, State 5 of New York, have invented certain new and useful Improvements in Centrifugal Liquid-Separators, of which the following is a specification, reference being had therein to the accompanying drawing.

10 This invention has relation to centrifugal machines, and more particularly to the separating-bowls thereof, and the principal object in view is to increase the rapidity with which the lighter constituent of a compound liquid 15 can be delivered from the bowl and yet prevent injury to the fiber or globules of said lighter constituent in the act of delivering the same.

Other objects and advantages of the invention will appear in the following description, 20 and the novel features thereof will be particularly pointed out in the claims.

Referring to the drawing, which is a substantially central vertical section of a separating-bowl and its immediate accessories, A represents the spindle of the machine; B, the upper portion of the frame-work; C, the receiver for the lighter constituent, which receiver is mounted upon the frame-work and provided 30 with a standard, C', jointed as at C'', for the support of the feed-pipe D, which is provided in this instance with a controlling-valve, D', and a discharge-conductor, E, and (in this instance) constructed in accordance with my invention as disclosed in my application, No. 35 236,584, pending herewith.

F represents the separating-bowl, which is provided with a neck, F', in this instance arranged at the bottom of the bowl, and having 40 a closed end, F'', in which the spindle A is seated.

G represents the supply-chamber, secured to the bottom and spindle by a screw or bolt, G', and provided with a supply-pipe, G'', which projects toward and near to the wall of the bowl F. A series of annular shelves, F'', extend from the inner surface of the walls of the bowl toward the center thereof, and each shelf is provided with a single port, F'', that 50 of one shelf being arranged at an opposite side of the bowl from that of the next adjacent

shelf. The discharge-conductor E is projected into the bowl and above the upper shelf of the series. The lower shelf projects inwardly beyond the walls F' of the neck F', and said neck is provided at its closed end with one or more ports, F'', for the delivery therefrom of a lighter constituent.

The bowl F is provided with an opening or mouth, F', into which the feed and discharge 55 pipes or conductors D and E are projected. If desired, the neck and the receiver may be extended beyond the walls of the bowl, as shown by dotted lines F'' and C' at the left of the drawing.

I have changed the general relative proportions of the bowl, its opening, its shelves or partitions, and the neck, in that the bowl is somewhat increased in diameter, the opening F' thereof is not contracted, but rather larger 60 than usual, the shelves or partitions are reduced materially in their relative width—that is, the distance from the wall of the bowl to the edge of each shelf or partition—and the neck is increased in its diameter, all of which changes 65 are for purposes which I will now describe.

Although the principal object in view is, as before stated, a material increase in the rapidity of the delivery of the lighter constituent, and this without injury to its fiber or 70 globules, still another object is to limit the lateral thickness or rather extent of the annular body of the heavier constituent of a liquid when the bowl is operating thereupon, and to prevent the lighter constituent from 75 rising above a certain point within the bowl during this operation.

Now, for the purpose of setting forth and clearly illustrating the operation of my invention, I will describe the same—as, for example, in separating cream from milk.

The milk is supplied through the pipe or conductor D, the quantity being controlled by the valve or cock D', as desired, and it falls into the supply-chamber G, and passes from 95 thence, through the pipe G'', into the space formed by the two lower shelves, F''. As the lower compartment of the bowl proper becomes filled the incoming milk will force any surplus upwardly through the port F'' into the 100 next compartment above, and so on until all the chambers or compartments are filled, it be-

ing understood, however, that immediately upon the entrance of the milk into the lower compartment centrifugal force acts to separate the cream from the milk, so that the latter occupies a space bounded substantially by the compartment—that is, by the wall of the bowl and opposite surfaces of adjacent shelves or partitions, as shown by the dotted line X—while the cream forms in an annular body, indicated by the dotted lines X and Y, the line Y indicating the inner vertical line of the annular body of cream as it is collected by the operation of the bowl. Now it will be seen that nothing but skimmed milk will be carried to the top of the upper shelf of the bowl, and this is insured by two facts: first, by reason of the separation of the compound liquid into several distinct portions, each being contained between two adjacent shelves, so that nearly all the cream in the milk admitted into the lower compartment is immediately separated, and such portions thereof as pass upwardly into the next compartment are immediately separated, and so on from compartment to compartment, so that the cream has been separated from the milk before the latter reaches the upper compartment. The other fact, which insures nothing but the entrance of skimmed milk upon the upper shelf, is that of the construction before described, whereby I expedite the delivery of the cream from within the body of the bowl, and this is accomplished in the following manner: By extending the neck F' outwardly beyond the opening F⁸, through which the neck F' communicates with the bowl F, I provide for the operation of centrifugal force upon the cream, and said force acts at the point where the cream enters the neck, so as to cause the cream with a greater or less force to move in a radial direction toward the wall F⁵ of the neck, and thus also to draw down the cream above. The curved portion X' of the cream-line indicates the point where the centrifugal force has the effect just mentioned. Now, instead of allowing the cream to immediately escape entirely from the bowl or from the neck while under the influence of centrifugal force, which influence would result in destroying the globules of the cream, it is cushioned by the cream already within the neck, and the injurious effect is obviated; and, furthermore, the cream is delivered from the neck by the action of gravity through the port or ports F⁶, of which I may have one or more, as desired. As the cream passes through the port it falls into the empty receiver first, but afterward into a greater or less quantity of cream within the receiver, and is again cushioned against injury. It is understood, of course, that the cream falls by action of gravity from the upper shelf down to the opening F⁸ of the bowl, so that in the delivery of the cream from the bowl as a whole I employ, first, the force of gravity, then centrifugal force, and, finally, again the force of

gravity. In this way I increase the rapidity with which the cream can be delivered from the bowl without injuring the globules thereof, and I also prevent the cream from rising above the upper shelf within the bowl, so that I can safely project my discharge-conductor directly into the bowl, instead of being required to form an additional annular chamber for the reception of the skimmed milk and for the operation of a discharge-conductor therein. 75

It is apparent that I can increase or decrease the amount of centrifugal force to which I subject the cream by increasing or decreasing the distance to the walls of the neck from the opening by which it communicates with the bowl. 80 As shown by dotted lines C' F'', I may even extend the neck beyond the bowl for the purpose of increasing the centrifugal force upon the cream. I may employ as many or as few shelves or partitions as desired. 85

Having described my invention and its operation, what I claim is—

1. A bowl for a centrifugal separator, having an annular shelf and a neck depending from the shelf outside of the inner edge thereof, 90 the bottom of the bowl being provided with a cream-outlet, substantially as specified.

2. A bowl for a centrifugal separator, provided with a depending neck and with a series of annular shelves or partitions, and having its bottom shelf projecting inwardly beyond the vertical walls of the depending neck, said neck having an outlet, substantially as specified, whereby the delivery of the cream or lighter constituent is accomplished, first, by 95 the action of gravity, then by centrifugal force, and, finally, by gravity.

3. A bowl for a centrifugal machine, with an outlet for a lighter constituent and having a series of shelves or partitions and a depending neck located beyond the inner vertical line of the edges of the shelves, in combination with a discharge conductor projected within the bowl and above the upper shelf thereof for discharging the heavier constituent, substantially 105 as specified.

4. The combination, with the bowl F, provided with port F⁶ and having the shelves F³, the openings F⁷ F⁸, and the neck F', having walls F⁵ outside of the edges of the shelves, of 115 the spindle A, supply-vessel G, having the pipe G², the receiver C, supply-pipe D, and the discharge-conductor E, substantially as specified.

5. The bowl F, provided with ports F⁶ and having the openings F⁷ F⁸, the shelves F³, provided with the ports F⁴, and the depending neck F', located beyond the inner vertical line of the edges of the shelves, substantially as 120 specified.

In testimony whereof I affix my signature in 125 presence of two witnesses.

CHARLES D. SHEPARD.
